(No Model.)

E. J. WILLIAMS.

VAPOR STOVE.

No. 372,586.

Patented Nov. 1, 1887.

UNITED STATES PATENT OFFICE.

EUGENE J. WILLIAMS, OF SPRINGFIELD, OHIO.

VAPOR-STOVE.

SPECIFICATION forming part of Letters Patent No. 372,586, dated November 1, 1887.

Application filed February 24, 1887. Serial No. 228,775. (No model.)

To all whom it may concern:

Be it known that I, EUGENE J. WILLIAMS, a citizen of the United States, residing at Springfield, in the county of Clark and State 5 of Ohio, have invented certain new and useful Improvements in Vapor-Stoves, of which the following is a specification, reference being had therein to the accompanying drawings.

This invention relates to certain new and 10 useful improvements in vapor-stoves designed with special reference to heating purposes and of peculiar applicability to stoves.

The object of my invention is to convert the 15 oil into a gas or vapor by the application of heat, the heat being supplied by the burner itself in such manner that it generates the gas as it uses it and superheats the same, so that it expands and effects economy in the quantity of oil used to generate the gas.

20 My invention to this end consists, essentially, of a pipe which conducts the oil from a suitable reservoir and constitutes a retort in which the gas is generated, as also a burner located with such reference to the retort portion of the pipe that the latter is subjected to the intense heat of the flame rising from the former, and in providing said pipe with an oil-sprayer located between the supply and the retort portion.

25 My invention further consists of a spraying-nipple having a stem which extends through it, and has a deflecting-head which shatters the small stream of oil into a fine spray.

In the accompanying drawings, forming a 30 part of this specification, and on which like reference-letters indicate corresponding features, Figure 1 represents a partial side and sectional view of my improved burner; Fig. 2, an end view thereof; Fig. 3, a plan view of 35 the flame-spreader, and Fig. 4 sectional views of the pipe and spraying-nipple.

40 Letter A designates a metallic shell, preferably of substantially rectangular form, and constructed of cast-iron, and having in its upper portion a series of holes, through which the flames pass, while the intermediate metal deflects and holds the flames somewhat against the retort. When this flame-spreader is placed in a stove fire-box, as the ordinary stove, and 45 it is desired to hold the flames to the front part of the stove, the damper B, composed of

a plate of iron, is turned to the position shown in Fig. 2 in full lines. When it is desired to let the flames pass to the rear of the stove and heat that portion, the plate is turned to the 55 position shown in dotted lines. Ledges C serve to hold the plate in position, the same being pivotally mounted on lugs D.

A pipe, E, leads from a suitable reservoir, F, in which the oil is contained, to the flame-spreader A. Passing under, it is bent at G and carried a second time under the spreader, and forms the burner portion H of the pipe. A series of small holes is formed in the upper 60 side of the burner H, through which the generated gases are emitted and at which points they are ignited. A narrow and shallow trough, I, incloses the numerous apertures, and serves to collect any oil that may pass out through the apertures before the gas has begun 65 to be generated, as when first lighted.

A cut-off, J, is placed at a convenient part of the pipe E, and in proximity to the spreader a sprayer is placed within the pipe and constructed to spray the oil flowing through it 70 into the portion K of the pipe which forms the retort or gas-generating chamber. This sprayer in the present instance consists of a metallic plug or nipple, L, fitted snugly into the pipe, and having a tapering hole there- 75 through and a funnel-shaped mouth at M. A small stem passes through the tapering hole and is secured at one end of the nipple to a cross-piece, as at N, and provided with a conical head, O, against which the fine stream of 80 oil forcibly strikes, and by which it is shattered into a fine spray. This spray issues into the retort K, and is converted into a combustible vapor or gas by the heat of the retort. The heat of the retort also raises the tempera- 85 ture of the gas generated and makes it expand and more readily burn, and acts to superheat it as the gas flows through the retort from the portion where it is essentially generated (near the left-hand end of the shell 90 A) across the same and toward the burner. The expansion produces more heat from the same quantity of gas than would be produced if it were not superheated. I do not here allude so much to an increased intensity of heat, 95 but more heat in point of time.

I desire to observe that I am aware that oil-

burners have been made in which the oil was heated as it passed on its way to the burner and was converted into a gas. In such instance, however, the oil was allowed to accumulate in quite a body as distinguished from being sprayed. The spraying process economizes in the consumption of the oil, enables the oil to be converted into gas quickly and at a lower heat, and prevents the objectionable accumulation of sediment and other residuum resulting from vaporizing the oil when in a body. With my improvement these objections do not exist, as I have ascertained by repeated trials, and an intense flame is produced and the spray is converted into gas at a much lower temperature, and therefore much sooner, than were the oil allowed to flow into the retort.

Having thus fully described my invention, what I claim as new, and desire to secure by Letters Patent, is—

1. In an oil-burner, the combination, with a reservoir, a pipe leading therefrom having a cock, a portion forming a retort, another por-

tion forming a burner having a series of perforations, and a trough thereon and located under the retort, of a flame-spreader located over the burner and incasing the retort, and a spraying-nipple within the pipe having a tapering hole and a stem with a conical head. 25

2. In an oil-burner, the combination, with a pipe one portion of which forms a retort, another portion of which extends beneath the retort portion and forms a burner, and yet another portion of which forms a conduit between the retort and the burner, of a hollow nipple and a flaring head near the discharge end thereof to spray the oil, and located in the said pipe near the retort portion and opposite to the end of the retort away from the end 35 which connects with the burner. 40

In testimony whereof I affix my signature in presence of two witnesses.

EUGENE J. WILLIAMS.

Witnesses:

CHASE STEWART,
EDWIN L. BRADFORD.

Corrections in Letters Patent No. 372,586.

It is hereby certified that in Letters Patent No. 372,586, granted November 1, 1887, upon the application of Eugene J. Williams, of Springfield, Ohio, for an improvement in "Vapor Stoves," an error appears in the printed specification requiring correction, as follows: In lines 6 and 10, page 1, the words "Vapor Stoves" should be stricken out, and the words *Oil Burners* inserted instead, and that the Letters Patent should be read with these corrections therein that the same may conform to the record of the case in the Patent Office.

Signed, countersigned, and sealed this 6th day of December, A. D. 1887.

[SEAL.]

D. L. HAWKINS,
Acting Secretary of the Interior.
